ISAAC J. LANE, OF TOPEKA, KANSAS

MAIL POUCH CATCHING AND DELIVERING MEANS

Application filed October 27, 1930. Serial No. 491,344.

My invention relates to improvements in a mail catching and delivering means.

The object of my invention is to provide means for the receiving and delivering of mail pouches simultaneously.

A further object of my invention is to provide mail pouch receiving and delivering means having toggle actuated jaws and mechanism for locking said jaws in closed position controlled by the size of the neck portion of the pouch and which is adapted to maintain the same in locked position until it is released by an operator in the mail car or at a station.

These and other objects will hereinafter be more fully explained, reference being had to the accompanying drawings which form a part of this specification, and in which like characters will apply to like parts in the different views.

Referring to the drawings:

Fig. 1 is a plan view of the crane and mail car with the jaws of the mail pouch catching and delivering means positioned in working relation to each other, parts being removed for convenience of illustration.

Fig. 2 is an elevation of Fig. 1, the car being in section taken on line 2—2 in Fig. 1.

Fig. 3 is an enlarged plan view of the jaw mechanism, parts being removed for convenience of illustration.

Fig. 4 is a view looking into the jaws when reversed, and showing a portion of the supporting means partly in section and parts removed for convenience of illustration.

Fig. 5 is a side view of the spring tensioned bar that is spaced downward from the jaws, shown partly in section for convenience of illustration.

My invention herein disclosed consists of a mail pouch supporting means rockably positioned within a mail car and extendable therefrom, and a crane stationarily supported in working relation to the mail car and having a supporting means for a mail pouch, by which means the outgoing and incoming pouches are exchanged and retained by the separate means respectively.

The means carried by the mail car consists of a vertically positioned column 1 de-

tachably arranged by inserting the upper end portion in an apertured plate 2 secured to the ceiling of the car and a plate 3 on the floor to receive the lower end of the column when the same is moved upward sufficient to seat therein, by which means the said column may be placed on either side of the door. It is understood that the plates will be employed for each side thereof. Positioned on the column is a collar 4 adjustable longitudinally therealong functioning as a stop for the apertured hub 5 of an arm 6, the said hub being revoluble on the column, by which means the arm is swung in and out of the car. The outer end of the arm is apertured and has a slot extending longitudinally of the arm a short distance and at right angles to the aperture, by which means clamping arms are formed which are held in clamping position by a bolt 7. Positioned in the aperture vertically is a leg 8 that is movable longitudinally and clamped in a desired position by the means above described. Rigidly attached and positioned at right angles and on the upper end of the leg is a sleeve 9 having a shaft 10 revolvably positioned thereon. The said shaft has a shoulder as at A on the outer end thereof to restrict an outward movement of the shaft. On the other end of the shaft is a head 11 detachably arranged for convenience of assembly thru the medium of a pin 11' extending thru the head and inner end of the shaft 10. The said head is bifurcated and has a sleeve 12 transversely extending therefrom for the purpose later described. Near each end of the bifurcation of the head members is a jaw member 13 pivotally attached to the head member and adapted to rock to and from each other simultaneously thru the medium of a toggle joint 14, the outer ends of which are pivotally connected to their respective jaw members, the adjacent or inner ends thereof being pivotally connected to a toothed rack 15, the said rack slidably engaging in the sleeve 12, by which means swinging movement of the jaw members with respect to the longitudinal axis of the rack is the same when the rack is moved outwardly or inwardly relative to the sleeve. The rack

has teeth B which are engaged by a spring tensioned pawl 16 pivoted on the sleeve 12 as shown in Fig. 3. It is understood that the closing of the jaws when placed in an open position is by contact of the neck C of a mail pouch 17 with the center portion of the toggle joint which in turn retracts the rack locking the jaws in their closed position as shown by dotted lines D in Fig. 3 thru the medium of the pawl as previously described, and to release the same the pawl is disengaged by compressing the leg portion thereof as at E.

Oppositely positioned on each side of the head is a spring tensioned finger 18 pivotally mounted on the head and adapted to swing in either direction as shown by dotted line F in Fig. 3. The said fingers have a laterally extending bend as at G, by which means an end portion thereof is spaced from the head and insertable thru a ring 19 positioned on either end of the mail pouch as shown in Fig. 2, by which means the pouch is vertically supported and attached to both ends thereof. It is understood that the outer point of the finger is seated in a notch in a boss 20 secured to the head or bar as the case may be and is removable therefrom when the pouch is received or delivered, the function of which is illustrated in Figs. 1 and 2.

The lower end of the pouch is attached to a similar finger to that described above, the said finger being carried by a bar 21 pivotally connected to an adjustably arranged hanger 22 that is secured to the lower end of leg 8 thru the medium of a set screw 23. The said bar has a downwardly extending portion as at 24 that is apertured to receive a pin 25 that is secured to the hanger and has a recoil spring 26 on the outer end thereof to engage snugly in a counter sink 27 in the said extended portion. The spring is compressed by a nut 28 threadedly engaging on the outer end of the pin to form resilient means to counteract the downward tension of the outer end of the bar 21. The bar is free to flex when engaging the lower end of a mail pouch, the length of which may vary.

In Fig. 1 the mail car is shown to be moving in the direction of the arrow H with the jaws of the members confronting each other and when traveling in the opposite direction the jaws are reversed by removing pins 29 and 30, so that the shafts carrying the jaws may be free to rotate and are held stationarily by reinserting the pins which engage in the aperture on the opposite side of the shaft. It will be understood that the receiving and delivering means that is carried by the car will be positioned on the rear side of the door with respect to the direction the car is moving, and is so positioned that the arm may contact on the jamb to prevent a backward rotation, and after receiving the pouch the

same may be swung into the car and removed therefrom by the mail clerk, and the pouch that is received by the crane stationarily positioned adjacent the track is free to revolve on the standard 31. The said standard is vertically carried by the base plate 32 which has an upwardly extending hub bored axially to receive the standard and means to secure the same therein.

On the upper end of the standard is a cantilever 33 adapted to rock from a horizontal to a vertical position as indicated by dotted lines J, as it is pivotally carried by a block 34 secured to the upper end of the standard. The block has a horizontally positioned seat in the upper end thereof in which the lever will rest horizontally. The said lever is equipped with a spherical weight 35 on one end thereof, the other end having a finger thereon as previously described. The weight functions as an overbalance to move the other end upward when the mail pouch is removed from the crane.

Intermediately positioned on the standard is a disc like member 36 concentrically attached and slantingly positioned with respect to a horizontal plane, the slant being downward and outward. The said disc functions as a track on which a rockably mounted arm element will slidably engage in its rotation around the standard. The said arm element is similar with respect to its operation to the sleeve 9 and the shaft 10, and a similar head and component parts is carried on the outer end thereof and is adapted to be reversed as previously described. The inner end of the arm is pivotally connected to the ears 37 of a sleeve 38 that slidably and revolvably engages on the standard, the arm being pivoted in such a way that the rocking movement thereof is restricted downward from a right angled position with respect to the sleeve and is stopped in its outward movement by contact of an intermediate portion thereof with the sleeve as shown at K in Fig. 2. It will be understood that the fingers on the head and the finger on the inner end of the cantilever will vertically align as supporting means for a pouch therebetween as shown in Fig. 2. The downward and outward slant of the disc is arranged to finally position the mail pouch at the outward side of the standard as shown by dotted lines L in Fig. 2.

Such modifications may be employed as lie within the scope of the appended claims, and having fully described my invention what I claim as new and desire to secure by Letters Patent is: —

1. In a mail pouch catching and delivering means, a bifurcated head having a sleeve laterally extending therefrom, a toothed rack slidably mounted within the sleeve, a spring tensioned pawl pivoted on the sleeve to engage the teeth, a pair of jaws pivotally at

tached to the head, and a toggle jointed element pivotally connected to the jaws and to the rack, by which means the jaws are opened and locked in a closed position, substantially 5 as shown.

2. In a mail pouch catching and delivering means, a rockably mounted arm carried by a mail car, a leg vertically carried by the outer end of the arm, a sleeve carried by 10 the upper end of the leg and positioned at right angles thereto, a shaft rotatably positioned in the sleeve and means to secure the same against rotation when selectively positioned, a head on the outer end of the shaft, 15 the head having a sleeve laterally extending therefrom, a pair of jaws pivotally carried by the head, a toggle joint element connecting the jaws, a toothed rack slidably mounted in the sleeve of the head and connected to the center joint of the toggle to 20 move the toggle to open the jaws, and a spring actuated pawl pivoted to the sleeve to engage the teeth of the rack as locking means to retain the jaws in locked position, a spring tensioned finger swingably mounted on the head 25 as carrying means for a mail pouch, and a similar finger vertically aligned with the first fingers, and means to carry the same on the other end of the leg, for the purpose 30 specified.

3. In a mail pouch catching and delivering means, a column, an arm swingably mounted on the column, a leg carried transversely on the outer end of the arm, reversibly arranged jaws and means to carry the same on the upper end of the leg and having spring tensioned means to pendently support a mail pouch, the jaws having a toggle joint, a rack and a pawl to lock the same 40 when closed by contact of the mail pouch with the toggle joint, a bar and a hanger carried by the lower end of the leg, the bar pivotally engaging on the hanger and spring tensioned means on the outer end of the bar 45 to connect with the lower end of the mail pouch.

4. In a mail pouch catching and delivering means, a standard and means to stationarily support the same in working relation 50 to a mail pouch catching and delivering means carried by a mail car, a cantilever transversely carried on the upper end of the standard and having spring tensioned means to pendently support a mail pouch, the said 55 cantilever being pivotally connected to the standard so as to move to vertical position by gravity when the mail pouch is released, an arm and a sleeve, said arm and sleeve being pivotally connected, the sleeve being 60 adapted to revolve and slide longitudinally on a standard, a disc having a hub axially carried on the standard, the disc portion being slantingly positioned and functioning 65 as a guiding means for the arm at the lower side thereof, toggle actuated jaws reversibly

arranged on the outer end of the arm, and a toothed rack to actuate the toggle to move the jaws to a closed position, and spring tensioned means on the outer end of the arm 70 to function as attaching means for the lower end of the mail pouch.

5. In a mail pouch catching and delivering means, a crane of the class described comprising a standard and stationary supporting means therefor, a seated block on the upper end of the standard, and a lever pivotally engaging at one end of the seat and adapted to rest therein horizontally, the lever having a spherical weight on the outer end thereof 75 to vertically position the same, a spring tensioned finger on the other end of the lever as pendent supporting means for a mail pouch, an arm and sleeve pivotally connected so that the arm transversely extends with respect to the axis of the sleeve, the sleeve being adapted to revolve and slide longitudinally on the standard, a head revolvably carried on the outer end of the arm as reversing means therefor, and means to stationarily support the head in a selected position, spring tensioned 80 fingers positioned on opposite sides of the head as attaching means for the lower end of a mail pouch, a pair of jaws extending from the head and pivotally connected thereto, a toggle jointed element connecting the jaws to move the outer ends of the same to and from each other, a toothed rack pivotally connected to the center joint of the toggle element and a spring actuated pawl to engage 85 with the teeth as a locking means for the closed position of the jaws, the jaws being closed by the contact of a mail pouch with the toggle element as it enters the jaws, a disc 90 axially carried by the standard and slantingly positioned with respect to the horizontal plane, the periphery of the disc being adapted to receive the load of the arm to 95 guide the same to the lower side thereof, all as and for the purpose specified.

In testimony whereof I affix my signature.
ISAAC J. LANE.
